(57) **CLAIM**

The ornamental design for an atomizer for electronic cigarette, as shown and described.

DESCRIPTION

FIG. 1 is a front elevational view of an atomizer for electronic cigarette showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof; and,

FIG. 8 is another perspective view thereof.

The broken lines in the drawings depict portions of the atomizer for electronic cigarette that form no part of the claimed design.

1 Claim, 8 Drawing Sheets
